(57) **CLAIM**

The ornamental design for a specimen cup sleeve with a retractable handle, as shown and described.

DESCRIPTION

FIG. 1 is an upper perspective view of the specimen cup sleeve with a retractable handle in a first position.

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is a rear perspective view of the specimen cup sleeve with the handle in an alternate position with phantom lines indicating the environment with which the specimen cup is used.
